UNITED STATES PATENT OFFICE

MORRIS ENGL AND GERHARD MIRUS, OF NEW YORK, N. Y.

DESIGN FOR A STATISTICAL CHART

Application filed March 3, 1931. Serial No. 38,918. Term of patent 3½ years.

To all whom it may concern:

Be it known that we, MORRIS ENGL and GERHARD MIRUS, citizens of the United States of America and Germany, respectively, both residing at New York city, in the counties of New York and Bronx, respectively, and State of New York, have invented a new, original, and ornamental Design for a Statistical Chart, of which the following is a specification, reference being had to the ac-

companying drawings, forming part thereof.

In the drawings:

Figure 1 is a plan view of the chart.

Figure 2 is an edge view.

I claim:

The ornamental design for a statistical chart as shown.

MORRIS ENGL.
GERHARD MIRUS.
